CLAIM

The ornamental design for a portion of a display screen with an icon, as shown and described.

DESCRIPTION

FIG. 1 is a front view of a first embodiment of a portion of a display screen with an icon showing our new design; FIG. 2 is a front view of a second embodiment thereof; FIG. 3 is a front view of a third embodiment thereof; and, FIG. 4 is a front view of a fourth embodiment thereof. The dot-dash broken lines in the drawings illustrate a portion of the display screen and form no part of the claimed design.

1 Claim, 4 Drawing Sheets
